CLAIM

We claim the ornamental design for a combination spoon and fork, substantially as shown and described.

DESCRIPTION

FIG. 1 is a front perspective view of a combination spoon and fork in accordance with the present design.

FIG. 2 is a back perspective view of the combination spoon and fork.

FIG. 3 is a front plan view of the combination spoon and fork.

FIG. 4 is a back plan view of the combination spoon and fork.

FIG. 5 is a right side elevational view of the combination spoon and fork.

FIG. 6 is a left side elevational view of the combination spoon and fork.

FIG. 7 is an enlarged upper end elevational view of the combination spoon and fork; and,

FIG. 8 is an enlarged lower end elevational view of the combination spoon and fork.

The broken lines show unclaimed regions for illustrative purposes and form no part of the claimed design.

1 Claim, 8 Drawing Sheets

Related U.S. Application Data

of application No. 15/268,175, filed on Sep. 16, 2016, which is a division of application No. 14/204,497, filed on Mar. 11, 2014, now Pat. No. 9,468,321.
